(57) **CLAIM**

The ornamental design for a display tray, as shown and described.

DESCRIPTION

FIG. 1 is a front perspective view of a display tray showing my new design;

FIG. 2 is a front elevational view thereof;

FIG. 3 is a side elevational view of the right-hand side thereof, the left-hand side view being a mirror image of FIG. 3;

FIG. 4 is a rear elevational view thereof;

FIG. 5 is a top plan view thereof; and,

FIG. 6 is a bottom plan view of my new design for a display tray in the open condition.

1 Claim, 4 Drawing Sheets

FIG. 2

FIG. 5

FIG. 6
